UNITED STATES PATENT OFFICE.

GEORGE W. LINDSEY, OF BALTIMORE, MARYLAND.

HAT-HOLDER.

SPECIFICATION forming part of Letters Patent No. 226,087, dated March 30, 1880.

Application filed January 21, 1880.

To all whom it may concern:

Be it known that I, GEORGE W. LINDSEY, of Baltimore city, State of Maryland, have invented certain new and useful Improvements 5 in Hat-Holders for Opera-Seats, &c.; and I hereby declare the same to be fully, clearly, and exactly described as follows, reference being had to the accompanying drawings, in which—

10 Figure 1 is a perspective view of a part of a row of opera-seats having the racks attached. Fig. 2 is a side elevation of the device detached from the seat.

The object of my invention is to furnish a 15 convenient rack or holder for supporting a hat or umbrella, or both, so constructed as to be readily attached to the ordinary seat, and adapted to swing out of the way against the back of the seat as persons pass between the 20 rows.

In the accompanying drawings, A A are the seats, o the backs of which are secured the racks a, as shown. These consist of wire bent into the shape shown in Fig. 2—namely, that

of the treble clef in music. This figure 25 furnishes a loop, b, upon which the hat is conveniently hung, and loops c and g for umbrellas or the opera-glass case.

The part d is made straight, and the whole device is secured to the seat by means of a 30 screw-eye, e, and staple f, in such manner as to swing freely from side to side and be out of the way as persons pass in or out between the rows of seats.

The device may be constructed and attached 35 at a trifling cost, is rather ornamental than otherwise, and its convenience and utility are at once evident.

What I claim is—

The rack herein described, consisting of a 40 wire bent into the form shown, whereby loops b g c are provided, and having a straight portion, d, in combination with the screw-eye e and staple f, as set forth.

GEO. W. LINDSEY.

Witnesses:

R. D. WILLIAMS,
JOHN C. GITTINGER.
